NONDETONATING ENGINE

Victor F. Zahodiakin, Forest Hills, N. Y.

Original application June 3, 1937, Serial No. 146,267, now Patent No. 2,120,344, dated June 14, 1938. Divided and this application June 13, 1938, Serial No. 213,537.

6 Claims. (Cl. 123—173)

This invention relates to internal combustion engines and is particularly directed to improvements in the construction of the cylinder head for the purpose of eliminating detonation. This is a division of Ser. No. 146,267, filed June 3, 1937, 2,120,344, patented June 14, 1938.

The invention is of primary value in connection with the L-head type of internal combustion engine. In the L-head design detonation occurs to a much greater extent and therefore presents a much greater problem than in that type of engine having an overhead valve, known as the valve-in-head type. This is true for the reason that the flame in the L-head type travels a greater distance, the spark-plug or point of ignition being located at a point offset from the cylinder. In the L-head type of engine combustion starts at the spark plug and moves across the combustion chamber until all of the mixture is burned. As the flame front moves across the combustion chamber, the pressure of the unburned portion of the mixture increases, which, of course, raises the temperature. At the same time radiation from the burning mixture heats up the unburned portion. Obviously, as the temperature of the unburned portion of the mixture rises high enough, an explosion occurs—i. e., the unburned mixture will explode instead of burning in an orderly fashion. This self-ignition creates a "knock" or results in the difficulties of detonation with which this invention is concerned.

Considerable experimentation and work have been done in attempts to eliminate detonation by varying the design and shape of the combustion chamber. However, it has been found in all cases that, regardless of the shape of the combustion chamber, when the ratio of compression reached a certain degree detonation occurred.

It is therefore an object of this invention to provide an improved cylinder head which includes a structure eliminating detonation and therefore all of its attendant disadvantages, such as excess vibration, rapid destruction of the engine, and power losses.

The present concept resides in a determination that heat dissipation must take place with increasing rapidity the further the flame proceeds from the point of ignition—that is to say, as the pressure of the unburned mixture tends to increase, and therefore its tendency to explode or pre-ignite increases, there should be facilities for dissipating the heat to keep the temperature of the burning mixture uniform.

The present invention provides a structural ar-

angement in the cylinder head whereby the heat dissipating properties of the combustion chamber increase evenly as the flame wall travels. Even-burning of the fuel is of vital importance in the elimination of detonation. Higher compression ratios are then possible, with the results of greater power output and noticeable economy for the given displacement.

Other objects and certain advantages will be more fully apparent from a description of the accompanying drawing, in which:

Fig. 1 is a transverse sectional view taken through an internal combustion engine of the L-head type incorporating the present invention, the section being taken through a cylinder thereof;

Fig. 2 is a sectional view taken on line 2—2 of Fig. 1, detailing the arrangement of the spurs or pegs within the water jacket;

Fig. 3 is a transverse sectional view of a cylinder head, illustrating a modified form of the invention;

Fig. 4 is a transverse sectional view taken similar to Fig. 3 and illustrating a further modification.

Referring to the drawing, the engine block is indicated at 5 and the cylinder head at 6. A cylinder of the cylinder block is indicated at 7 and includes the usual piston 8. Inasmuch as the present invention is entirely concerned with the problems arising from inefficient combustion or improper burning of the fuel mixture introduced into the cylinder, the intake passageways in the combustion chamber are shown in detail. The intake passageway 9 enters the side of the cylinder block and turns upwardly for entrance into the combustion chamber 10 formed as a recess in the bottom of the cylinder head. The cylinder head and cylinder block include the usual water jacket.

The valve 11 controls the admission of the fuel mixture to the cylinder. This valve is reciprocably mounted in the cylinder block and has its head engaging a seat 12 formed in the block by countersinking the upper end of the intake passageway. Substantially above the valve 11 will be found a spark plug 13 disposed in the head 6 in the usual manner with its point located in the combustion chamber 10 of the cylinder head. A substantial chamber is provided in the cylinder head at that portion between the spark plug and the valve. From this point towards the cylinder the wall 15 of the cylinder head—i. e., the top of the combustion chamber—slopes downwardly toward the top of the cylinder and then

continues straight across to form a slight recess of a form in outline of the curvature of the cylinder as at 16. This shallow or relatively flat recess indicated at 16 may be referred to as a zone in which detonation most readily occurs. The wall 15 referred to as a top wall of the combustion chamber includes an arrangement of heat-dissipating spurs or pegs 17 extending or projecting into the water chamber thereof.

10 The upper wall 18 of the cylinder head has one or more large circular clean-out openings therein. These openings are provided for the purpose of permitting access to the interior of the water chamber in the dissipating spurs or studs for removal of the cores used in the casting process. Inasmuch as these spurs are formed by casting, it may be necessary to clean up any unnecessary projection by sand-blasting. This is accomplished through the opening and thereafter 15 through the access provided by said opening it is possible to remove the same in ground-off particles. These openings are closed by means of disks 20 seated in the countersunk portion 21. Initially, as shown, the disks are concave fitting 20 snugly in the countersunk portion 21. After the core removing and blast cleaning operation these disks are placed in position and secured permanently by applying pressure to their surface, pressing the central portions thereof into the 25 plane of the outer edges. This operation swages the disks in position.

Again referring to the heat dissipating spurs or pegs, it will be noted that these spurs increase in height uniformly. Their respective heights 30 increase as the distance from the point of ignition increases. As will be observed in Fig. 2 the spurs are arranged so as to increase and arrange the heat dissipating area proportionately to the tendency toward temperature rise. The 35 spurs are disposed substantially within the outline of the cylinder and the aggregate areas of the spurs provide increased heat dissipating areas toward the point A, which is that portion of the combustion chamber in which the fuel mixture 40 is last to burn.

Referring to Fig. 1 a series of lines emanating from the point of ignition are indicated at 22. These are indicated to mark the progress of the flame wall. As stated, the letter A indicates that 45 portion of the combustion chamber in which the fuel mixture is last to burn. Now, as the flame wall progresses across from the point of ignition and over the piston the temperature of the unburned portion, as at A, increases with the resulting tendency to pre-ignite or explode. However, this tendency to cause temperature rise is evenly counteracted by the ability of a top wall of the combustion chamber to dissipate the generated heat. It is emphasized that there is perfect 50 proportion between the two forces at all times—i. e., the tendency toward temperature rise and heat dissipation. The ability of the cylinder head to dissipate the heat generated in the combustion chamber is directly proportionate to the tendency toward temperature rise. That is to say, an absolute balance is brought about whereby the temperature of burning at point A is exactly the same as that at the point of ignition.

The spurs or pegs are cast integrally with the 55 cylinder head and are tapered to the extent that the operation of the casting is greatly facilitated. The spurs are tapered to the degree necessitated by the core operation.

In the modification of Fig. 3 it will be noted 60 that the studs are of uniform height and provide

uniform heat dissipating areas. If a sufficient number is provided to provide proper cooling of the zone of detonation while at the same time maintaining normal temperature of the internal combustion engine where detonation does not 65 usually occur. The spurs are located directly above the zone where detonation usually occurs and are disposed in parallelism with the axis of the cylinder or, in other words, at 90° to the horizontal wall of the cylinder head disregarding the 70 sloping portion.

In the design shown in Fig. 4, the cylinder head walls are arranged as in the preceding forms with the exception that the lower wall 23 or top wall of the combustion chamber decreases in thickness from the point of ignition to the point A— that is to say, the greater the distance the wall is from the point of ignition the less mass it has. In order to properly support this wall of decreased thickness or cross-section, a series of 20 struts 24 is provided disposed parallel to the axis of the cylinder and between the top and bottom walls of the head and within the water jacket. The spaces between these struts decrease as the distance the struts are from the ignition point 25 increases.

I claim:

1. A head for the cylinder block of an internal combustion engine, said cylinder block including gas inlet and outlet passageways and cylinders 30 opening to the top of the block, said head being of hollow form to provide a water jacket and including recesses in its underside providing combustion chambers when disposed on said block over said passageways and cylinders, the walls of 35 the combustion chamber decreasing in thickness as they are more distant from the gas inlet, said decrease in thickness occurring substantially constantly along the entire path of flame travel.

2. A head for the cylinder block of an internal 40 combustion engine, said head being of hollow form to provide a water jacket and including a recess in its underside providing a combustion chamber when disposed on said block, said head including means for mounting an ignition device 45 toward the side thereof, the inner surface of the wall of said recess being smooth and uninterrupted, said wall being of reduced thickness, said reduced thickness occurring substantially constantly from the means for mounting the ignition 50 device to the far side of the combustion chamber and therefore providing progressively decreased mass as it is more distant from the means for mounting the ignition device.

3. A head for the cylinder block of an internal 55 combustion engine, said head being of hollow form to provide a water jacket and including a recess in its underside providing a combustion chamber when disposed on said block, said head including means for mounting an ignition device 60 toward the side thereof, the inner surface of the wall of said recess being smooth and uninterrupted, said wall being of reduced thickness providing progressively decreased mass as it is more 65 distant from the means of mounting the ignition device, and struts between the walls of the recess and the adjacent walls of the water jacket.

4. A head for the cylinder block of an internal combustion engine, said cylinder block including gas inlet and outlet passageways and cylinders 70 opening to the top of the block, said head being of hollow form to provide a water jacket and including recesses in its underside providing combustion chambers when disposed on said block over said passageways and cylinders, said com- 75

5 combustion chambers having smooth uninterrupted internal surfaces, said combustion chamber walls being of less thickness in cross-section as they are closer to the tops of the cylinders, and struts between the combustion chamber walls and the upper walls and within the water jacket, said struts being spaced closer together as the wall decreases in thickness.

10 5. A cylinder head provided with a water-jacket defined by a lower thin combustion chamber wall and an upper wall, and struts between said

walls, said struts supporting the walls over the entire extent of the lower thin combustion chamber wall.

6. A cylinder head provided with a lower thin combustion chamber wall and an upper wall defining a water jacket, and heat-dissipating means reinforcing said lower wall, said heat dissipating means supporting the walls over the entire extent of the lower thin combustion chamber wall. 5
